Term of patent 14 years

(Cl. D95—5)

Fig. 2.

Fig. 1.

Fig. 3.

FIG. 1 is a front elevational view of an electric scissors showing my new design;

FIG. 2 is a top plan view of the electric scissors shown in FIG. 1;

FIG. 3 is a bottom plan view of the electric scissors shown in FIG. 1;

FIG. 4 is a rear elevational view of the electric scissors shown in FIG. 1;

FIG. 5 is an end elevational view as seen from the left of FIG. 1;

FIG. 6 is an end elevational view as seen from the right of FIG. 1; and

FIG. 7 is a perspective view as seen from the front right corner of the electric scissors shown in FIG. 1.

The dominant features of the design reside in the handle shown in full lines, the conventional scissors blades being shown in broken lines.

I claim:

The ornamental design for an electric scissors, substantially as shown and described.
